(57) **CLAIM**

The ornamental design for a shoe upper, as shown and described.

DESCRIPTION

FIG. 1 is a side elevational view of a shoe upper according to the present invention, within a first environment of use. FIG. 2 is a perspective view thereof.

FIG. 3 is a side elevational view of the shoe upper within a second environment of use.

FIG. 4 is a perspective view thereof.

FIG. 5 is a side elevational view of the shoe upper within a third environment of use.

FIG. 6 is a perspective view thereof.

FIG. 7 is a side elevational view of the shoe upper within a fourth environment of use.

FIG. 8 is a perspective view thereof.

FIG. 9 is a side elevational view of the shoe upper within a fifth environment of use.

FIG. 10 is a perspective view thereof.

FIG. 11 is a side elevational view of the shoe upper within a sixth environment of use.

FIG. 12 is a perspective view thereof.

FIG. 13 is a side elevational view of the shoe upper within a seventh environment of use.

FIG. 14 is a perspective view thereof.

FIG. 15 is a side elevational view of the shoe upper within an eighth environment of use.

FIG. 16 is a perspective view thereof.

FIG. 17 is a side elevational view of the shoe upper within a ninth environment of use.

FIG. 18 is a perspective view thereof.

FIG. 19 is a side elevational view of the shoe upper within a tenth environment of use.

FIG. 20 is a perspective view thereof.

FIG. 21 is a side elevational view of the shoe upper within an eleventh environment of use.

FIG. 22 is a perspective view thereof.

FIG. 23 is a side elevational view of the shoe upper within a twelfth environment of use.

FIG. 24 is a perspective view thereof.

(Continued)

FIG. 25 is a side elevational view of the shoe upper within a thirteenth environment of use; and,
FIG. 26 is a perspective view thereof.
The broken lines in the drawings represent environment that form no part of the claim.
